(57) **CLAIM**

I claim the ornamental design for a portable charger travel case, as shown and described.

DESCRIPTION

FIG. 1 is an isometric view of a portable charger travel case showing my new design;

FIG. 2 is bottom view of my portable charger travel case thereof;

FIG. 3 is a top view of my portable charger travel case thereof; FIG. 4 is a left side view of my portable charger travel case thereof;

FIG. 5 is a right side view of my portable charger travel case thereof;

FIG. 6 is a front elevational view of my portable charger travel case thereof;

FIG. 7 is rear elevational view of my portable charger travel case thereof; and,

FIG. 8 is an elevational view of the inside of my portable charger travel case thereof.
